UNITED STATES PATENT OFFICE

2,518,991

LEATHER-CUTTING TOOL

Walter Kolodnicki, New London, Conn.

Application October 30, 1945, Serial No. 625,486

1 Claim. (Cl. 30—293)

1

This invention relates to a tool for cutting leather into narrow strips or lace.

An object of this invention is to provide an improved leather-cutting tool which may be adjusted to cut different widths of strips from a piece of leather and which may also be adjusted to accommodate different thicknesses of leather.

A further object of this invention is to provide an improved tool for cutting leather into narrow strips or thongs in which the blade is adjustable to cut varying widths of strips and in which a gauge block is adjustable to admit leather of varying thicknesses.

Still another object of this invention is to provide an improved lace-cutting tool for leather which is so constructed as to cut a length of lace spirally from the center of an odd-shaped piece of leather.

Other objects of this invention will appear from the following specification and claim and from the accompanying drawings illustrating the invention, wherein:

Figure 1 is a front elevational view of the cutting tool with the parts assembled in operative position;

Figure 2 is a side elevational view of the cutting tool assembled for operation;

Figure 3 is a rear elevational view with the gauge block partially cut away and partially disassembled to show the construction;

Figure 4 is a sectional view taken on line 4—4 of Figure 1 and showing the knife construction;

Figure 5 is a detail view of the knife blade holder; and

Figure 6 is a fragmentary piece of leather showing the manner in which a lace is cut spirally from the middle portion thereof.

Referring to the figures, 1 is the handle and 2 is the body of the cutting tool. The body has a narrow upstanding lug 3 having a slot 4 therein. A gauge block 5 is carried by a threaded screw 6 extending through slot 4 and having a knurled thumb-piece 7 on its end. Rotation of the screw 6 while gauge block 5 is held from rotation will cause the gauge block to approach lug 3 until it abuts said lug, as shown in Figure 1. The slot 4 permits the distance between the block 5 and the body 2 to be varied, and tightening of the thumb-piece 7 will hold the gauge block 5 in any adjusted position relative to the body 2.

The body 2 is provided with a horizontally extending slot 8. Extending through slot 8 is a threaded knife blade holder 9 having a slot 10 therein for receiving a knife blade 11. A knurled nut 12 is provided for holding the blade 11, in-

2

serted in slot 10, against the body 2 and the gauge block 5. As can be seen from Figure 4, the blade is inserted in slot 10 so that the knife edge bears against the body 2 and the block 5. The slot 8 permits the blade to be adjusted horizontally to vary the distance between the blade 11 and the lug 3. The nut 12 will hold the knife in any adjusted position. The gauge block 5 has its face scored to indicate units of distance from the lug 3.

In operation, assuming the parts are in the position shown in Figure 1, if the notch 13 formed between the gauge block 5 and the body 2 does not conform to the thickness of the leather to be cut, it is necessary to first loosen block 5 slightly by turning the screw 6. This will enable block 5 to be pushed up or down to provide for notch 13 being of the right size to admit the thickness of the leather. Screw 6 is tightened in the adjusted position. It is then necessary to adjust the position of knife blade 11 so that its distance from the lug 3 conforms with the width of the lace or strip it is desired to cut from the piece of leather. This adjustment is accomplished by loosening the nut 12 slightly, moving the holder 9 and blade 11 to the proper position, and then tightening the nut 12.

To cut a strip from the leather piece, it is merely necessary to push the forward end of the piece of leather into notch 13 with one side of the piece of leather abutting the lug 3. Then while the cutting tool is held in one hand, the other hand is used to draw the piece of leather through the cutting tool while maintaining the piece of leather against the lug 3. A thong or strip whose width conforms to the distance between the blade 11 and the lug 3 will thus be formed. The operation will be facilitated if a small cut is first made in the forward end of the piece of leather so that the forward end of the piece of leather will protrude through the cutting tool slightly to facilitate gripping.

The cutting tool is so constructed as to enable a thong to be cut out of the center of an odd-shaped piece of leather. As seen in Figure 6, a portion 14 about the size of a quarter is first cut out of the center of the leather piece. Then a circular cut 15 is started for about an inch and a half and of the desired width to form the beginning of the thong. Then the piece of leather is inserted in notch 13 with the lug 3 extending through the opening 14, and the end 15 of the thong fitting into the space between the lug 3 and the blade 11. To enable placing the leather in this position, the knife blade 11

is first loosened and rotated or lowered to clear the notch 13, and after the piece of leather is slipped over the tool, the blade 11 is returned to its proper position. With the leather in position as indicated above, it is merely necessary to pull on the end 15 of the thong while holding the tool, and the blade 11 will cut a thong spirally from the piece of leather while the leather rotates. Thus, this cutting tool permits the cutting of thongs from odd pieces of leather that are normally discarded as scrap.

While a certain specific embodiment of this invention has been shown, it will be understood that various modifications may be made within the spirit of the invention. Therefore, no limitations on the invention are intended other than are imposed by the scope of the appended claim.

I claim:

A lace cutter, comprising a handle, a flat body plate secured to one end of the handle and extending forwardly of the handle and provided with a slot extending transversely of the handle, the forward transverse edge of the body plate remote from the handle being straight and parallel to the slot, an integral longitudinal extension carried by the body plate at one forward corner of the same and having its inner longitudinal edge arranged at right angles to the forward transverse edge, the longitudinal extension having a longitudinal slot formed therein in the longitudinal axis of the last named slot being arranged at right angles to the longitudinal axis of the slot in the body plate, a flat rectangular gage block arranged adjacent to the forward transverse edge and longitudinal extension and having a straight edge to abut against the inner longitudinal edge of the extension and a straight edge at right angles to the first-named straight edge and parallel to the forward transverse edge, the gage block having

a transverse screw threaded opening in its straight edge adjacent to the longitudinal extension, an adjusting screw mounted within the transverse screw threaded opening and extending slidably through the slot in the longitudinal extension and having a clamping head to engage the outer edge of the extension so that the gage block may be adjusted longitudinally toward and from the forward transverse edge of the body plate, the gage block being provided upon one side and adjacent to the forward transverse edge with transversely spaced width measuring graduations, a pin slidably mounted within the slot of the body plate and arranged at right angles to the longitudinal axis of such slot and screw threaded at one end, the pin having a longitudinal slot near its opposite end, a longitudinally extending straight knife blade mounted within the slot of the pin and extending longitudinally forwardly of the body plate and over the face of the gage block having the width measuring graduations, the knife blade contacting the adjacent faces of the body plate and gage block and being slideable transversely over the same, the knife blade being arranged at right angles to the forward transverse edge, and a nut mounted upon the screw threaded end of the pin and disposed upon the opposite side of the body plate for clamping the knife blade between one end of the slot of the pin and the adjacent face of the body plate.

WALTER KOLODNICKI.
